UNITED STATES PATENT OFFICE.

GEORGE A. BONELLI, OF KINGMAN, ARIZONA.

MOLDING APPARATUS.

Application filed June 24, 1922. Serial No. 570,570.

To all whom it may concern:

Be it known that I, GEORGE A. BONELLI, a citizen of the United States of America, residing at Kingman, in the county of

5 Mohave and State of Arizona, have invented certain new and useful Improvements in Molding Apparatus, of which the following is a specification, reference being had thereto in the accompanying drawing.

10 My invention relates to improvements in molds for use in molding concrete blocks or columns and has for its object to provide a mold capable of ready removal from the formed object, and capable of repeated use.

15 In the drawings—

Fig. 1 is a transverse sectional view of the mold employed in forming the hollow concrete slabs used in the construction of said building.

20 Fig. 2 is a side elevation of a fragment of one end of the mold shown in Fig. 1.

Figure 3 is a transverse vertical sectional view of the mold employed in producing a coping or balustrade, and,

25 Fig. 4 is a side elevation of a fragment of one end of the mold illustrated in Figure 3.

As shown in the drawings, in the form of the blocks 33 I employ an inner collapsible 30 form having two halves 36—36, and an outer form comprising side members 37, and bottom plates 92—92 contoured to support the strip 38 in Fig. 1, to form the groove 35; said outer form having at its top the flared 35 open mouth 39 to form the tongue 34.

The strip 38 rests upon the flanges 91, which flanges 91 are integral with the bottom strips 92; each of said strips 92 carries an ear 93, which ears 93 are joined by the 40 links 94 to the frame members 40 and 41 respectively so that the separation of said members 40—41 (see dotted lines in Fig. 1) will thrust the strips 92—92 inwardly to release the block formed within the mold;

45 the members 40—41 are hinged to the brackets 95—95 by the pins 96. Said outer form 37 is mounted in a frame comprising the two parts 40—41, the part 40 having the cross bar 42, the part 41 having the cross bar 43. A hand-lever 44 is secured to the bar 42 by the pivot 45. The lever 44 has a longitudinal slot 46 engaged with a pin 47 set in the cross-bar 43, so that the operation 50 of the lever 44 serves to compress the frame 37 into position for use in molding the concrete block 33, or to open said form 37 at

its top and sides to release the formed block 33, as indicated by dotted lines in Fig. 1. The said mold has a flat end closure 85 as shown in Fig. 2.

60 One of the inner-form members 36 (see Fig. 1) is expanded or contracted by means of the rods 48—49, having an eccentric connection 50 which is rotated to force said rods 48—49 outwardly, expanding the form-member 36 to which they are attached to operative position, or to draw said rods 48—49 toward each other to contract said member 36 and permit it to be withdrawn from the form and said concrete block 33; 70 when the opposing member 36 may be readily flexed and withdrawn.

75 In forming the hollow fence or balustrade 14 the mold shown in Fig. 3 is employed; in which mold the inner form 51 is a single metallic sheet and is expanded or contracted in the usual manner by the hinged-bars 52. The outer form comprises a single metallic sheet 53, having at its upper edge a funnel 54 for the purpose of flowing the concrete, 80 and having its flanges 55—55 spiked or otherwise secured to the wooden foundation mold 56. A suspension pin 57 is mounted transversely through the form 53 to support the inner form 51 (see Fig. 3) and said pin 85 57 is left in place when the balustrade 14 has been formed and the outer form 53 removed therefrom, when the protruding ends of the pin 57 will be cut off flush with the face of the formed concrete. The inner form 51 being formed of a single metallic sheet its over-lapping edges 81 and 82 are held in juxtaposition by the spring 83; and said form 51 is provided near its opposite end with the handle 84. Such removal is 90 accomplished by detaching the form 53 from the base 56. Said mold (of Fig. 3) has a flat end-closure 90 as shown in Fig. 4.

95 In the use of the apparatus freight and material costs, and labor conditions will determine whether to build the blocks, pipe-connections and other parts to be incorporated, near or remote from the building site; and like economic conditions will determine how much of the structure shall be 100 flowed in place and how much built of previously prepared constituent parts. Hence the described apparatus is devised to meet shifting labor conditions and shifting sources of material supply, as well as variable freight rates.

105 Having thus described my invention, what

I claim as new, and desire to secure by Letters Patent, is—

1. In a mold apparatus, a mold body formed to provide longitudinally separable mold parts, other mold parts arranged at one end of said longitudinally separable mold parts, jaws embracing said first mentioned mold parts and pivoted adjacent to one of their ends for swinging movement, means cooperative with the other ends of said jaws for alternately locking the same in a mold closing position, and to separate them to collapse said mold parts, and means connecting the pivoted ends of the jaws with the last mentioned mold parts for moving the latter correspondingly with the swinging movement of said jaws.
2. In a mold apparatus, a mold body formed to provide vertical longitudinally separable mold parts, other mold parts arranged at the lower sides of said vertical mold parts, vertically disposed jaws embracing said mold parts and pivoted for swinging movements adjacent their lower ends, means cooperative with the upper ends of said jaws for alternately locking the same in mold closing position and to separate

them to release said mold parts, and means connecting the lower ends of said jaws with said last mentioned mold parts for moving the latter correspondingly with the swinging movements of said jaws.

3. In a mold apparatus, a mold body formed to provide vertical longitudinally separable parts, other separable mold parts arranged at one end of said vertical mold parts, a base disposed below said mold parts, vertically disposed jaws embracing said vertical mold parts and pivoted adjacent their lower ends to said base for swinging movements to and from mold closing position, means cooperative with the upper ends of said jaws for locking the same in their mold closing position and to separate them to release said mold parts, and means connecting the lower ends of said jaws with said other mold parts for moving the same to and from closed position correspondingly with the swinging movements of said jaws and said vertical mold parts.

In testimony whereof I have hereunto affixed my signature.

GEORGE A. BONELLI.
